UNITED STATES PATENT OFFICE

JOHN WALDHEIM, OF ELIZABETH, NEW JERSEY, ASSIGNOR TO UNDERWOOD ELLIOTT FISHER COMPANY, OF NEW YORK, N. Y., A CORPORATION OF DELAWARE

TYPEWRITING MACHINE

Application filed May 29, 1925. Serial No. 33,609.

In the patents to McLaughlin, No. 1,488,453 and Corcoran, No. 1,509,828, is shown a standard Underwood typewriting machine comprising a base or framework portion with 5 an overhanging paper-carriage thereon, the framework being encased in a pack which includes walls of sheet-metal and linings of felt or other sound-absorbing material; said pack not only dampening the vibrations of 10 the framework at the operation of the machine, but also serving as an air-pocket absorbing sound-vibrations.

One of the features of the present invention is the provision of an overhead sound-subduing chamber or pocket co-operative with said pack and directly enclosing the paper-carriage. In designing said overhead pocket, compactness has been sought, and also ready adaptability to typewriting machines 20 of standard construction. To secure these ends and to provide an overhead air-pocket which will co-operate efficiently with said framework pack, said carriage-pocket is designed to travel with the carriage, and for 25 this purpose is of light construction, and also in the preferred form has provision for the accommodation of the work-sheets at the rear of the carriage. This overhead pocket comprises top, side, front and rear walls, and 30 sets down over the carriage, being open at the bottom to co-operate with said pack in confining and absorbing sound of operation.

While said overhead pocket or carriage enclosure is shown in the preferred form in 35 combination with a machine-frame pack, still the invention is not limited in all cases to the use of a pack.

In using sound-deadening typewriter-cabinets, in which a capacious base is closed 40 by a wide cover, it has been found that such cabinets cannot be conveniently used in the regular drop-top typewriter-desks, because of their carriage-accommodating extensions, which overhang the cabinets at the sides, and 45 prevent the lowering of the cabinets into the desks.

To avoid such an objection, the pack and carriage-enclosure are preferably made in 50 separate units, the pack fitting the frame of the machine, and the canopy over the car-

riage being borne by or traveling with the carriage, and being made of substantially the same width. This effects a reduction of the space required, and, when the carriage is centered relatively to the machine-frame, it 55 may be dropped into the desk-compartment.

The carriage pocket or casing is pivotally mounted at the rear of the carriage and is swingable upwardly and rearwardly, away from the platen, to render the work-sheet 60 accessible and to facilitate the manipulation thereof. However, when the work-sheet is placed around the platen, the carriage is operable from the outside of the casing, provision being made for the protrusion of the carriage-control levers to the outside of the pocket. In this manner it is possible to return and line-space the carriage and to release the same, and also to rotate the platen by the hand-wheels independently of the line-space lever while the carriage remains encased. The construction of the carriage-enclosing casing permits the use of an Underwood standard typewriting machine with 65 no alteration thereof. It has been customary to extend the carriage-control lever to the outside of the usual cabinet through cushion-sealed slots, a feature which involved the changing of the carriage-control lever. 70

The carriage-casing is preferably provided 75 with a rear auxiliary pocket to receive the overhanging portion of the work-sheet.

The pack is provided with a front plate fast to the machine-frame and the plate has an arcuate opening in front of the type-basket. The opening is provided with a detachable closure secured to the plate by means of clips. The top of the frame is also completely covered or closed against the emission of sound-waves, except for an opening necessary to connect the carriage and its operating mechanism in the machine-frame. Said top closure serves as a lower closure for the carriage-casing when the same is in its central position. 85

The carriage-casing is provided with an opening to render the work-sheet visible at the printing point. Said opening may be closed by a glass plate. 90

In the preferred form of the present in- 95

vention, the main frame of the machine is enclosed by a single unit, pack or shoe having a floor, side walls and a rear wall. There is also provided a front wall which may be mounted on the front of the main frame to form a front closure. A casing is provided which extends over the typewriter-carriage, and it is provided with side walls, a rear wall and a front wall, said carriage-casing being 5 pivotally supported in one form of the invention on brackets secured to the carriage of the machine. The top edges of the side walls of the pack conform substantially in outline to the outline of the lower edges of 10 the side walls of the carriage-casing, and extend closely toward each other to minimize the escape of sound from the sides of the machine.

There is also provided a partition which 20 forms the ceiling of the pack and forms the floor of a chamber formed by the carriage-casing. This partition may be composed of individual sections, one of which is herein disclosed as attached to the removable front 25 plate, the other sections being supported directly on the main frame of the machine. Said cover and said partition are all lined with felt to absorb the sound-waves.

It will be understood that the pack with 30 said partition may be used to a fair degree of sound-muffling efficiency without the carriage-casing, and that the latter may be used with the partition to a fair degree of efficiency without the pack, and, further, that the pack 35 may be used with the carriage-casing without said partition. A higher degree of sound-muffling efficiency is produced, however, by using the three elements, namely, pack, partition and carriage-casing in combination.

40 The carriage-casing is constructed so as to expose the usual platen-rotating knobs, the line-space handle, the carriage-return finger-piece and the carriage-release handle, so that said finger-pieces may be manipulated while 45 the casing is in its effective position over the carriage. To this end, the side walls of the casing are provided with cutouts through which the platen-shaft extends, upon the ends of which shaft the finger-pieces are mounted 50 outside of the casing. The forward corners of said casing are indented to expose at one side the line-space handle and at the other side the carriage-return finger-piece and the carriage-release handle, so that they may be manipulated while the casing remains in its effective position.

55 The casing is provided at its rear end with an auxiliary pocket to receive the overhanging end of a work-sheet extending from the platen of the machine. This auxiliary pocket may be closed at the bottom and is curved to cause the paper to curl up within said pocket.

60 In one form of the invention, the carriage-casing, instead of being supported on the typewriter-carriage, is supported on a sub-

carriage arranged to travel back and forth on a rail, which rail may be secured to the rear of the pack. In this form the sub-carriage is provided with an auxiliary pocket to form a continuation of the paper-pocket on 70 the cover, in which the work-sheet hangs. A connecting bar, extending between the typewriter-carriage and the sub-carriage, causes said carriages to travel in unison.

75 Other features and advantages will hereinafter appear.

In the accompanying drawings, 80 Figure 1 is a front view, in elevation, of an Underwood standard typewriting machine enclosed in the sound-deadening casing.

Figure 2 is a side elevation of the machine, 85 showing the casing partly in cross-section, the cover-part being shown in dot-and-dash lines in its open or displaced position.

Figure 3 is a detail showing the carriage-operating levers and a portion of the cover-part of the casing.

Figure 4 is a perspective view of the machine-carriage and the cover therefor.

Figure 5 is a perspective view of the pack 90 for enclosing the frame of the machine (not shown).

Figure 6 is a plan view of the top closure of 95 the body-part, showing the machine with the carriage removed.

Figure 7 is a side view of the machine, 100 showing a portion of the pack and the top closure.

Figure 8 is a cross-sectional view through 105 the line 8—8 of Figure 6.

Figure 9 is a side view of the casing and the machine enclosed therein, showing a modified form of the carriage-cabinet having an opening at the rear thereof for the overhanging portion of the work-sheet.

Figure 10 is a rear view of a modified form 110 of the invention shown in Figure 11.

Figure 11 is a side view, in elevation, of the casing and the machine enclosed therein, showing a modified form of the invention in 115 which the carriage-cabinet is borne by rails fast to the pack or body-part.

The Underwood standard typewriting machine includes a frame 10 supported by feet 11. Extending forwardly from said frame there is provided a keyboard-extension 12, in which there are mounted banks of keys 13, said keys being depressible to swing type-bars 14, designed to strike a platen 15, around which there is provided a work-sheet 16. The platen is shiftably mounted on a platen-frame 17 borne by a carriage 18, and the carriage is mounted upon rails 19 and is disposed for letter-space travel at each key-depression.

120 In order to control the movement of the carriage and the platen, there are provided a line-space lever 20, effective to return the carriage while line-spacing the platen, a carriage-release lever 21, effective to disconnect the carriage from the escapement-mechanism 125

(not shown), and a carriage-return finger-piece 21.

For the purpose of deadening the sounds arising from the operation of the machine, the frame 10 is enclosed within a pack comprising a bottom wall or sole 22, two side walls 23 closely fitting the frame of the machine at the sides thereof, and a rear wall 24 also closely fitting the frame. At the front the pack is open to clear the keyboard-extension except for a low wall 25 under the keyboard. The frame of the Underwood machine is provided with openings 26, both at the sides and at the rear thereof, for the purpose of rendering the mechanism in the frame more accessible. In this invention, the casing is provided with a felt lining 27 for the purpose of closing said openings and to absorb or deaden the sound as near as possible to its source. The top of the frame is also provided with a felt closure to prevent the emission of sound through openings at the top, clearance being provided for the free operation of some of the parts of the mechanism which protrude therethrough to support and control the carriage. As shown in Figure 5, the top closure comprises two rear plates, two side plates and two front plates. The left-hand rear top closure, indicated by the numeral 28, is inserted from the rear of the machine and is clamped to the frame 10 by means of tabs 29 projecting downwardly from a frame 30, to which there is secured a piece of sound-deadening material indicated by the numeral 31. At the center of the sound-deadening material there is provided an opening or window 32 through which the carriage-return band 33 of the machine is passed. The right-hand rear top closure 34 comprises a frame 35 secured to the frame of the machine by means of a screw 36, to which the carriage-return band is secured. A felt piece 37, having holes 38 and 39 respectively designed to clear the back-space link 40 and the ribbon-shift connecting link 41, is glued or otherwise secured to the frame 35, the frame and the felt piece being provided with an open slot 42 for the purpose of clearing the tabulating key mechanism 43.

To further enclose the upper portion of the frame, there are provided end closures 44. Said closures comprise frames 45 and felt pieces 46 fast thereto. Said pieces are secured to the machine by means of inwardly-bent tabs 47 projecting from downwardly-extending ribs 48, the tabs 47 engaging an opening in the frame. The end closures are also provided with clearance openings 49 for the ribbon-spool shafts 50.

At the front, the opening overlying the type-basket is provided with another closure 51, also comprising a frame 52 and a felt piece 53 fast to the frame. The frame is provided with slots 54 to clear the ribbon-feed mechanism, and also with a clearance cutout

55 for the type-bars. The frame is reinforced by means of cross-ribs 56, and has an arcuate rear edge 57 to close as much as possible of the opening over the type-bars.

The front opening of the machine-frame is provided with a plate 58 secured thereto by means of screws 59 fitting into holes 60. This plate is substituted for the regular front plate of the Underwood machine which is designed to protect the mechanism within the frame. Said plate is also provided with an arcuate opening 61 in front of the type-bars to facilitate the cleaning thereof. In this invention, there is provided a front closure comprising a plate 62 and a felt lining 63. The plate is designed to overlap the opening and is provided with inwardly bent tabs 64 engaging the plate 58 to thus support the closure thereon. In order to facilitate the removal of the front closure there is provided a finger-piece 65 fast to the plate 62.

The carriage-cabinet is illustrated in its preferred form in Figures 1, 2, 3 and 4, and comprises side walls 66 forming an integral part of an arcuate top 67 which extends rearwardly and downwardly at 68, forming a rear pocket 69 to house the overhanging unused portion of the work-sheet. The cabinet is pivotally mounted upon brackets 70 fast to the carriage by means of screws 71. The brackets 70 extend rearwardly and downwardly from the carriage to lower the fulcrum point of the cabinet. In order to facilitate the assembling of the cabinet upon the carriage, there are provided fulcrum studs 72 having on each a reduced portion 73, at the ends thereof, engaging with holes in the brackets 70. The studs are screwed into a tapped hole 74 in the sides of the cabinet.

One of the features of this invention is that the carriage of the machine is completely operable from the outside of the cabinet, and, to this end, provision is made for the protrusion to the outside of the cabinet of the line-space lever 20, the carriage-release lever 21 and the finger-wheels 75 at the ends of the platen 15. In this manner it is possible to completely manipulate the work-sheet during the typing operation except for the replacement of the work-sheet, in which case the cabinet is swung rearwardly away from the platen and is held in an open position as shown in dot-and-dash lines in Figure 2 by its own weight and by the action of balancing springs 76. The springs 76 are operatively mounted between two studs 77 and 78, the former fast to the brackets 70 and the latter fast to the side walls of the cabinet to assist, by their closing tension, to both open the cabinet and hold it in its open position.

In order to render the work-sheet visible at the printing point, there is provided an opening 79 at the top of the cabinet, in the path of the line of vision of the operative, said opening being preferably closed by means

of a transparent plate 80 to prevent the emission of sound therethrough. The plate is preferably made of glass and is secured to the top wall of the cabinet by engaging its forward edge in a groove 81, the rear edge 82 being secured to the cabinet by means of clips 83.

The top of the cabinet is extended forwardly and there terminates in a downwardly-extending short wall 84 which overlaps the front plate 58 of the pack. In order to prevent the escape of sound between the wall 84 and the platen 58, there is provided a felt strip 85 secured to the plate. As it is desirable to enclose as much as possible of the carriage, and at the same time it is desirable to render the carriage-control levers accessible without displacing the cabinet, there is provided a cut-away portion at each side of the opening 79 to thus clear the carriage-control levers and permit their operation. The cut-away portion is enclosed by front walls 86 and side walls 87, the latter conforming to the side guard of the carriage. At the rear, the cabinet extends downwardly and forwardly, forming a curvate wall 88, which wall extends again upwardly, forming a straight wall 89 substantially parallel to the rear wall 68, and terminates with an edge 90 partly cut away to clear some of the mechanism when the cabinet is swung to an open or displaced position. To further deaden the sounds arising from the operation of the machine, the carriage-cabinet is provided with a lining of sound-deadening material, indicated generally by the numeral 91.

In another form of this invention, the carriage-cabinet is provided with an opening 92 at the rear for the overhanging portion of the work-sheet. Said form of the invention is illustrated in Figure 9.

In order to relieve the carriage from the weight of the cabinet, there is provided mechanism in another form of the invention illustrated in Figures 10 and 11. Said mechanism comprises a rail 93 fast to the rear wall 24 of the pack, upon which rail there is mounted a box-like member 94 disposed for lateral travel therealong. The member 94 is provided with wheels 95 revolvably mounted thereon, the wheels having a V-shaped periphery engaging with rounded edges 96 of the rail 93. In this manner the friction of the wheels upon the rail is reduced to a minimum and at the same time the member 94 is slidably positioned on the rail. The member is provided with a lining 97 of sound-deadening material and comprises end walls 98 provided with studs 99 upon which the cabinet is rockably mounted.

The cabinet in this case is not supported by the carriage at 100 as in the preferred form, but is supported upon its rear end, the whole weight thereof being borne by the member 94.

It will be noted in this connection that the

sides of the cabinet are provided with clearance cuts 101 to clear the platen-axle 102 when the platen is shifted to upper-case position. The modified form of the invention is illustrated in Figure 11, in which the cabinet is shown in both closed or effective and open positions, the latter position being shown in dot-and-dash lines. There are also provided compensating springs 103 to assist in displacing the cover which is held in its open position by its own weight holding the sides of the cabinet against studs 104 projecting from the member 94, upon which studs one of the ends of the springs 103 is anchored. The other ends of the springs are secured to studs 105 fast to the side walls of the cabinet. The weight of the cabinet is borne by pins 106 fast to the member 94, and the front portion of the cabinet hangs over the carriage.

In order to drive the cabinet and its supporting member 94 along with the carriage, there is provided a connecting piece 107 secured to the carriage at 108 by means of screws 109; said piece 107 extends downwardly and is provided with a slot 110 engaging with a pin 111 fast to the member 94.

To facilitate the construction of the pack, and in order that the same pack may be used either with a supported or unsupported cabinet, the rail 93 is made of a separate part and is fastened to the rear wall of the pack by means of screws 112.

Heretofore it has been customary to extend the carriage-control levers to the exterior of the sound-proof casing through openings in front thereof. Said levers had to be elongated in order to facilitate the operation from the outside of the casing. In this invention, owing to the manner in which the carriage-cabinet is designed, it is possible to use the same levers as provided in the Underwood machine, thus eliminating the cost of replacing the levers.

Variations may be resorted to within the scope of the invention, and portions of the improvements may be used without others.

Having thus described my invention, I claim:

1. The combination with a typewriting machine, including a main frame and a carriage, of a sound-muffling device, said device including a casing to enclose the frame of the machine, a casing to substantially enclose the carriage, and sound-muffling means arranged under the carriage and above the main frame, said sound-muffling means forming a substantially closed ceiling for the frame-casing and a substantially closed floor for the carriage-casing.

2. The combination with a typewriting machine, including a main frame and a carriage, of a sound-muffling device, said device including a casing to enclose the frame of the machine, a casing to substantially enclose the carriage, and sound-muffling means arranged

under the carriage and above the main frame, said sound-muffling means forming a substantially closed ceiling for the frame-casing and a substantially closed floor for the carriage-casing, said carriage-casing being arranged to travel with said carriage.

3. The combination with a typewriting machine, including a main frame and a carriage, of a sound-muffling device, said device including a casing to enclose the frame of the machine, a casing to substantially enclose the carriage, and sound-muffling means arranged under the carriage and above the main frame, said sound-muffling means forming a substantially closed ceiling for the frame-casing and a substantially closed floor for the carriage-casing, said carriage-casing being supported on said carriage to travel therewith.

4. The combination with a typewriting machine, including a main frame and a carriage, of a sound-muffling device, said device including a casing to enclose the frame of the machine, a casing to substantially enclose the carriage and to travel with said carriage, and a paper-pocket at the rear of said carriage-casing to receive the overhanging end of a work-sheet from the carriage.

5. The combination with a typewriting machine, including a carriage having a finger-piece thereon, of sound-muffling means including a cover for said carriage to travel with said carriage, said cover having an indentation at one of its corners to expose the finger-piece, so that said finger-piece may be manipulated while the cover is in its effective position.

6. The combination with a typewriting machine, including a carriage having a line-space lever at one end and a carriage-release lever at the other end thereof, of sound-muffling means including a cover for said carriage to travel with said carriage, said cover having indented corners at its forward end, the line-space lever projecting from the carriage into one indented corner and the carriage-release lever projecting into the other corner, so that both levers may be independently operated while the cover is in its effective position.

50 7. The combination with a typewriting machine, including a carriage and a platen on said carriage, of sound-muffling means including a cover for said carriage and mounted to travel therewith, said cover including a rear wall terminating at a sheet-deflecting pocket to receive the end of a work-sheet overhanging the platen.

8. The combination with a typewriting machine, including a carriage and a platen on said carriage, of sound-muffling means including a cover for said carriage and mounted to travel therewith, and a pocket at the rear of said cover, travelling with the same, to receive the overhanging end of a work-sheet on said platen.

9. The combination with a typewriting machine, including a main frame and a carriage having standard carriage controlling means, of a sound-muffling device including a casing to enclose the main frame, and a cover having side walls for said carriage, said cover being mounted to travel with said carriage over the frame-casing, said side walls on said cover having recesses through which the carriage-controlling means projects to enable the carriage being wholly controlled from the exterior of the casing.

10. The combination with a visible typewriting machine having a carriage and finger-pieces on said carriage, of a cover extending over said carriage and traveling therewith, said cover having indentations at its forward corners to expose said finger-pieces, and a window between said indentations through which the printing point may be observed.

11. The combination with a typewriting machine having a carriage and a platen on said carriage, of sound-muffling means including a cover for enclosing said carriage and mounted to travel therewith, said cover including a rear wall formed into an enclosing pocket to accommodate the overhanging end of a work-sheet extending from the platen.

12. The combination with a typewriting machine, including a carriage, of sound-muffling means including a cover for said carriage, said cover having a pocket at its rear end and extending downward from said carriage, and brackets on said carriage, said brackets reaching into said pocket to pivotally support said cover below the plane of the carriage.

13. The combination with a typewriting machine, including a main frame and a carriage thereon, of sound-muffling means including a casing to enclose the main frame at the sides, front, back and bottom, and a plurality of closure devices to substantially close the top of said casing, said closure devices being located in substantially parallel planes at the top of said frame and uniformly below said carriage, forming a sound-baffle therebetween.

14. The combination with a typewriting machine, including a main frame, a front plate thereon supported thereby, a carriage, a platen on said carriage, and type-bars to print against said platen, of sound-muffling means including a casing to enclose the main frame at the sides, back and bottom, and a plurality of closure devices to substantially close the top of said casing, said closure devices being located in substantially parallel planes at the top of said frame and uniformly below said carriage to form a sound-baffle therebetween, one of said closure devices being supported by said front plate and arranged above the type-bars.

15. In combination with a typewriting machine having a platen and a carriage, a sound-deadening hood movable with and enclosing said carriage, and pivotal means on the carriage for rendering the hood displaceable between fixed stop positions for facilitating the manipulation of a work-sheet around the platen. 70
16. In combination with a typewriting machine having a platen and a carriage, a sound-deadening cover movable with and enclosing said carriage, and means for rendering the cover displaceable away from said platen for facilitating the manipulation of a work-sheet, said cover including end walls forming an integral part of a curvate top, and said top extending rearwardly and downwardly and forming a pocket for receiving the unused portion of the work-sheet and providing a pivotal position for the cover. 75
17. In combination with a typewriting machine having a platen and a carriage, a sound-deadening cabinet wholly supported by said carriage, and means for rendering the cabinet displaceable for facilitating the manipulation of a work-sheet, said means including brackets fast to the carriage to pivotally support the cabinet and studs in the side walls of the cabinet to limit the movement thereof in two directions. 80
18. In a typewriting machine having a carriage, a platen shiftably mounted on said carriage, a lever for line-spacing the platen and for returning the carriage, carriage-feeding mechanism, a lever for disconnecting the carriage from said feeding mechanism, and finger-wheels for rotating the platen, a sound-deadening hood wholly supported by the carriage, said hood completely enclosing said carriage except for the platen and carriage control levers and for the platen-rotating wheels, and said hood being pivotally mounted on the carriage in a manner to afford the displacement of the hood away from the platen and from said platen and carriage controlling means, for rendering the platen accessible and for manipulating a work-sheet. 85
19. In a typewriting machine having a traveling carriage and a frame supporting the same, rigid noise-muffling means including a sound-baffle arranged below said carriage in order to lie between the same and said frame in such manner as to acoustically isolate said carriage from said frame. 90
20. The combination with a typewriting machine having a traveling carriage mounted on a frame, of sound-muffling means including a pair of relatively stationary baffle-walls arranged beneath and above said frame, respectively, the latter being located between said frame and carriage, in order to acoustically isolate one from the other, and a third baffle-wall superposed in spaced manner above the upper frame-baffle so as to overlie said carriage and travel therewith. 95
21. The combination with a visible typewriting machine having a traveling carriage mounted on a frame, of a cover mounted on the carriage to travel therewith and normally envelope the same and provided both with a visual window and with a pocket spaced from said window for receiving the overhang of a work-sheet projecting from said carriage. 100
22. The combination with a visible typewriting machine having a traveling carriage mounted on a frame and provided with finger-pieces, of a cover for the carriage to travel therewith and normally envelope the same, provided rearwardly with a pocket to receive the overhang of a work-web from said carriage, and provided forwardly with a window for viewing the printing point and with indentations on both sides of said window to expose said finger-pieces for manipulation. 105
23. In a typewriting machine having a frame, a key-board and a traveling carriage, the combination with a sound-muffling casing completely enclosing said frame while exposing the keyboard, a sound-muffling enclosing cover associated with said carriage in such manner as to envelope the same and travel therewith, and an intermediate stationary baffle-means secured to the frame to acoustically divide said casing from said carriage-cover to constitute said casing and said cover as two acoustically isolated units. 110
24. In a typewriting machine having a frame, the combination with a traveling carriage, of a sound-muffling cover for enclosing said carriage, and means to render the cover displaceable and to hold the same in register with the carriage so as to travel therewith, including a rearward pocket forming part of said cover, and rigid projections associated with said carriage in such manner as to extend into said pocket and pivotally support said cover within said pocket. 115
25. In a typewriting machine having a frame and a traveling carriage thereon, the combination with a sound-muffling casing for enclosing said frame, a pivotally mounted sound-muffling cover enveloping said carriage in such manner as to travel therewith and to be relatively displaceable in order to completely expose said carriage, and an auxiliary sound-baffle on said frame interposed between the same and said carriage to acoustically isolate the frame-casing from said carriage-cover. 120

JOHN WALDHEIM.
